UNITED STATES PATENT OFFICE

RAYMOND E. ACKLEY, OF CHICAGO, ILLINOIS, ASSIGNOR TO R. R. DONNELLEY AND SONS COMPANY, OF CHICAGO, ILLINOIS, A CORPORATION OF ILLINOIS

BOOK-SEWING MACHINE

Application filed September 14, 1928. Serial No. 305,968.

My invention relates more particularly to machines for sewing together the sheets from which books are to be made.

One of my objects is to provide a construction of machine whereby the output from machines of this general character may be increased.

Another object is to provide a machine for this purpose which, in its operation, will not be liable to impairment.

Another object is to provide a book-sewing machine which will sew the books by a lock stitch located along one edge of the book.

Another object is to provide mechanism by which the books are fed in accurately timed relation to the operation of the stitching mechanism presenting, among other advantages, the elimination of an unsightly groove across the end of the book produced, in the trimming operation, by the cutting through the stitch when the first stitch through the book is not located at the proper distance from the end of the book.

Another object is to provide means, cooperating with the needle, for preliminarily piercing the work to avoid undue stress on the needle and permit of the free withdrawal of the needle from the work; and other objects as will be manifest from the following description.

Referring to the accompanying drawings:-

Figure 1 is a plan view, with certain parts of the sewing-machine proper broken away, of a machine embodying my invention.

Figure 2 is a view in side elevation of the machine.

Figure 3 is a similar view of the machine but viewing it in another direction, a portion of the work feeder being shown in transverse section.

Figure 4 is a view in sectional elevation of reciprocating and rotating awl-mechanism forming a part of the machine.

Figure 5 is a plan sectional view of a detail of the mechanism for rotating the awl, the section being taken at the line 5 on Fig. 6 and viewed in the direction of the arrows.

Figure 6 is a section taken at the line 6-6

on Fig. 5 and viewed in the direction of the arrows.

Figure 7 is a plan view of one of the elements of the book-feeding mechanism the dotted lines together with the full lines representing the element by a developed view.

Figure 8 is a view in end elevation of the element of Fig. 7; and

Figure 9, a perspective view of the presser-foot of the sewing machine.

The particular illustrated embodiment of my invention comprises a hopper, or magazine 10, for the books to be sewed and mounted at its open bottom on the bed 11 of the machine.

The books are placed in the hopper to extend in a vertical series with the edges thereof to be stitched extending lengthwise of the bed, the pile of books thus presented resting on the bed.

The front end of the hopper and from which the books are fed, in succession as hereinafter described, contains, at its lower edge, a slot 12 of a height slightly greater than the thickness of the book and through which the lowermost book passes.

The feeding of the books, one thereof being shown at 13, from the hopper 10 and through the machine, is effected by an intermittently-operating conveying mechanism comprising an endless conveyor chain 14, supported, and driven, by sprockets 15 and 16 provided on shafts 17 and 18 on the frame of the machine. The chain 14 extends lengthwise of the machine and is provided at intervals with book feeding lugs, shown as in the form of angle irons, which project upwardly through a slot 20 in the bed 11, the lugs 19 operating, in succession, to engage the lowermost books in the hopper and move them out of the latter and through the stitching mechanism hereinafter described.

The chain 14 is driven by power applied to the shaft 18 as from a continuously operating shaft 21 shown as driven by a belt 22 engaging a pulley 23 on the shaft 21. The intermittent actuation of shaft 18 is effected by the mechanism shown in Figs. 5, 6, 7 and 8 and comprising a shaft 24 journalled in a housing 25 carried by the frame of the ma-

chine and having a bevel gear 26 meshing with a bevel gear 27 on shaft 21. The shaft 24 is provided with a worm wheel 28 of the construction shown in Figs. 6, 7 and 8 and in the form of a mutilated worm comprising a rib 29 extending peripherally about the shaft 24 with its ends represented at 30 and 31 deflected in opposite directions and spaced apart as represented at 32 to form a sectional spiral groove. The mutilated worm 28 meshes with a gear 33 rigidly secured to the shaft 18, the construction of this drive mechanism being such that for each rotation of the shaft 24 the gear 33 and shaft 18 are rotated a distance 15 equal to the distance between adjacent teeth of this gear, the shaft 18 being thus moved throughout a portion only of a complete rotation of the shaft 24, namely, throughout substantially one-quarter revolution only of this shaft, thereby producing an intermittent movement of the conveyor 14.

The machine also comprises chain stitch sewing mechanism which, except as to the features hereinafter described is of the same 25 construction as the commonly known wax thread type of sewing machine, the sewing machine mechanism shown comprising, generally stated, a depending reciprocating boring tool, which by way of example and as 30 shown, may be an awl, arranged in vertical alinement with an upwardly extending reciprocable hook needle, the awl, in descending, operating to penetrate the work and the needle operating through the hole made by 35 the awl and by hooking over the thread at the upper side of the work, in the lowering of the needle, drawing the thread in looped condition downwardly through the opening, the needle and awl operating in timed relation 40 to perform the operation stated.

In machines of the wax thread type as commonly provided the needle is caused to operate not only as stated, but also back and forth in the line of feed of the work while 45 extending into the opening produced by the awl, to effect feed of the work, but as the above referred to back and forth movement of the needle is not desirable in book sewing I dispense with the mechanism producing such movement of the needle, whereby the 50 needle remains at all times in vertical alinement with the awl, and feed the work by the conveyor mechanism above described.

Furthermore, while I retain the mechanism 55 which operates to reciprocate the awl, I have supplemented such mechanism with mechanism whereby the awl, while engaging the books, is caused to rotate therein to thereby reduce the amount of power required to drive 60 the awl through the books.

In the machine shown the sewing machine proper is represented at 34, the reciprocating and rotating awl at 35, and the needle at 36. As the mechanism for reciprocating the awl 65 and needle in properly timed relation to effect

the boring and the stitch-forming operations is well known, description thereof appears to be unnecessary, it being sufficient to state that these parts are operated by the main drive shaft 37 of the machine shown as driven, by a belt 38, from the drive shaft 21, it being understood that during a portion of the cycle of operation of the machine the awl 35 is raised above, and the needle 36 is lowered below, the upper surface of the bed 11 along 70 which the books to be sewed are advanced beneath, and in engagement with, a vertically-reciprocable presser foot 34^a as shown in Fig. 3. The presser-foot 34^a, in accordance with machines of the common form above referred to, is reciprocated in timed relation to the needle and awl to engage the books during the operation of the needle and awl and be raised to permit of the feeding of the books when both the needle and awl are in 75 withdrawn position.

The awl 35 is reciprocated by means of a pitman 38 pivoted at its lower end, as indicated at 39, to an awl-holder 40 which is 80 guidedly mounted, at its upper end, to reciprocate, the upper end of the pitman 38 being journaled on the pin 41 of a crank 42 secured to the end of the shaft 37.

The guide for the upper end of the awl-holder 40 comprises, in accordance with the 85 illustrated embodiment of my invention and constituting a feature not present in the common form of the above-referred-to type of machine, a hollow vertical shaft 43 journaled at ball-bearings 44 in the head 45 of the sewing machine and provided internally with diametrically-opposed keys 46 held against lengthwise movement by shoulders 47 on the opposite ends thereof, the keys 46 extending into keyways in the holder 40 whereby rotary 90 driving connection between the holder 40 and the shaft 43 is provided while permitting of the reciprocation of the holder 40 in the shaft 43 and along the keys 46.

The shaft 43 is provided with a pulley 48 95 which is connected by an endless belt 49 with a pulley 50 on the drive shaft 51 of a motor represented at 52 and mounted on the body of the machine.

The intermittent drive mechanism for the 100 conveyor 14 is so constructed and timed relative to the operation of the sewing machine proper that the conveyor chain operates to feed the books only during those periods when both the awl and the needle are in withdrawn position relative to the books and the presser foot 34^a is raised.

Assuming that the conveyor 14 has fed the forwardmost one of the books removed from the hopper, into the space between the needle and the awl, and that the book is at rest, the presser foot 34^a lowers into engagement with the book, the rotating awl 35 descends, boring a hole in the book along one edge thereof, the awl then rising and the needle moving 105 110 115 120 125 130

upwardly through the hole made by the awl and hooking over the thread at the upper side of the presser foot 34^a and represented at 53. The needle then descends, while the awl 5 35 remains in raised position, drawing the looped thread downwardly through the hole in the book. The presser foot 34^a then rises and the conveyor 14 operates to advance the books along the bed a predetermined distance 10 equal to the length of stitch which it is desired be produced in the book. Following the discontinuation of the feed as stated, the presser-foot, awl, and needle again operate to repeat the operations just 15 scribe and the books again advanced a distance equal to the length of stitch to be made, these operations continuing as long as books continue to be supplied to the hopper.

Commenting on certain advantages of a 20 machine constructed in accordance with my invention, it will be noted that thereby a book may be sewn with a lock stitch, without danger of impairment of the parts, including the needle; that by providing the conveyor 25 which not only feeds the books from a pile thereof to the sewing mechanism but also constitutes the feed for the books in passing through this mechanism by which they are sewed, the books are fed to the sewing mechanism in accurately timed relation to the operation of the latter ensuring the location of the first stitch for each book at the proper point for avoiding the production of an unsightly groove across the end of the book in, 30 the trimming operation; and that by providing for the vertical alinement of the awl and needle at all times, danger of the catching of the hook of the needle on the edge portion of the hole produced by the awl is 35 prevented.

While I have illustrated and described a particular construction embodying my invention, I do not wish to be understood as intending to limit it thereto as the same may 45 be variously modified and altered without departing from the spirit of my invention.

What I claim as new, and desire to secure by Letters Patent, is:

1. In a sewing machine, the combination 50 of a reciprocable needle, means for forming a hole in the work in axial alinement with said needle, means for reciprocating said needle, and intermittently operating means for feeding the work through the machine 55 when said first-named means and needle are withdrawn from the work.

2. In a sewing machine, the combination 60 of a reciprocable needle, a reciprocable and rotatable boring tool in axial alinement with said needle, means for reciprocating said needle, means for reciprocating and rotating said tool, and intermittently operating means for feeding the work through the machine when said boring tool and needle are with- 65 drawn from the work.

3. In a chain-stitch sewing machine, the combination of a reciprocable hook-needle, means for forming a hole in the work in axial alinement with said needle, means for reciprocating said needle, and intermittently operating means for feeding the work through the machine when said first-named means and needle are withdrawn from the work. 70

4. In a chain-stitch sewing machine, the combination of a reciprocable hook-needle, a reciprocable and rotatable boring tool in axial alinement with said needle, means for reciprocating said needle, means for reciprocating and rotating said tool, and intermittently operating means for feeding the work through the machine when said boring tool and needle are withdrawn from the work. 75

5. In a book-sewing machine, the combination of a reciprocable hook-needle, means for reciprocating said needle, means for presenting the thread to the hook of the needle, a reciprocable and rotatable boring tool in axial alinement with said needle, means for reciprocating and rotating said tool, and means for feeding a book through the machine, all of said means operating in timed relation to first bore a hole in the book, then project the needle through the hole and thereafter feed the book. 80

6. In a book-sewing machine, the combination of sewing mechanism, a hopper adapted to contain a plurality of books, book-feeding means operating to feed the books one at a time from the hopper to and through said sewing machine. 100

7. In a book-sewing machine, the combination of sewing mechanism, a hopper adapted to contain a plurality of books and intermittently operating book feeding means operating to feed the books one at a time from the hopper to and through said sewing mechanism. 105

8. In a book-sewing machine, the combination of means for forming a hole in the book, a reciprocatory needle positioned in axial alinement with said first-named means to enter the hole made by the latter, means for reciprocating said needle, and means operating to feed the book after withdrawal of the needle from the hole in the book, whereby the book is at rest during the forming of the hole therein and during the movement of the needle into, and out of, said hole. 110

9. In a sewing machine, the combination of a reciprocable needle, a hole-forming device in axial alinement with said needle, means for reciprocating said needle, and intermittently operating means for feeding the work through the machine when said device and needle are withdrawn from the work. 120

10. In a sewing machine, the combination of a reciprocable needle, a hole-forming device in axial alinement with said needle, means for reciprocating said needle, means 130

for reciprocating said device, and intermittently operating means for feeding the work through the machine when said device and needle are withdrawn from the work.

11. In a chain-stitch sewing machine, the combination of a reciprocable hook-needle, a hole-forming device in axial alinement with said needle, means for reciprocating said needle and intermittently operating means for feeding the work through the machine when said device and needle are withdrawn from the work.

12. In a chain-stitch sewing machine, the combination of a reciprocable hook-needle, a hole-forming device in axial alinement with said needle, means for reciprocating said needle, means for reciprocating said device, and intermittently operating means for feeding the work through the machine when said device and needle are withdrawn from the work.
